OF CARTHAGE, MISSOURI.

SYNCHRONOUS TRANSMITTER.

1,377,844.

Specification of Letters Patent. Patented May 10, 1921.

Application filed September 10, 1919. Serial No. 322,993.

(FILED UNDER THE ACT OF MARCH 3, 1883, 22 STAT. L. 625.)

To all whom it may concern:

Be it known that we, BRUNSON S. McCUTCHEON, United States Army, a citizen of the United States, stationed at Washington, 5 D. C., and HAROLD E. WILLIAMS, a citizen of the United States, and a resident of Carthage, county of Jasper, and State of Missouri, have invented an Improvement in Synchronous Transmitters, of which the following is a specification.

The invention described herein may be used by the Government or any of its officers or employees in prosecution of work for the Government or by any other person in the 15 United States, without payment of any royalty thereon.

The object of our invention is to provide a novel device for duplicating and indicating the motion of a remote rotating body, 20 and the invention is particularly concerned with the provision of such a device which will be simple in construction, practical to manufacture, and thoroughly reliable and efficient in operation.

25 The accompanying drawings disclose an exemplary embodiment of the underlying principles of the invention. Briefly described:—

Figure 1 is a front elevation of a preferred form of the device of our invention, the dial-plate being broken away;

Fig. 2 is a view in side elevation thereof, the dial-plate being shown in section;

Fig. 3 is a view in front elevation of a 35 somewhat modified form of our invention, the dial-plate being broken away;

Fig. 4 is a view in side elevation of the device shown in Fig. 3, the dial-plate removed; and

40 Fig. 5 is a diagram of the electric circuits for both forms of our invention.

Referring now in detail to the drawings:—

45 1 designates a shaft rotatably supported in suitable bearings (not shown).

An arm 2 is fast, at one end, on said shaft and loosely carries, at its other end, a rotatable pinion 3.

50 Also loosely supported on said shaft 1 is a pair of beveled gears 4, 4 meshing with the pinion 3.

The beveled gears are secured to or are integral with ratchet-wheels 5, 5, the teeth of which are reversely or oppositely cut, so

that the ratchet-wheels are reversely rotatable. The ratchet-wheels 5, 5, are provided with hubs 6, 6 loose on shaft 1. Wound on said hubs, in opposite directions, are cables 7, 7 carrying, at their lower ends, weights 8, 8.

Carried fast on the shaft 1 is a pointer 9, coöperating with a stationary calibrated dial-plate 10 carried by a bracket or stationary support (not shown).

The ratchet-wheels are provided with suitable escapement mechanism, which, in this instance, comprises rockers 11, 11 pivoted or fulcrumed intermediate their ends on a pivot-pin 12 supported in any suitable manner. Each of the rockers is provided, at 70 points removed from the ends thereof, with upward projecting fingers 13, 14 coöperating with the adjacent ratchet-wheel 5. Carried by one end of each rocker is an armature 15 attracted by an electro-magnet 16 disposed 75 therebeneath. A coil spring 17 secured to the other end of each rocker 11, maintains it in an inclined position, with its armature out of contact with the magnet when the latter is not energized, and with the finger 80 13 in engagement with the teeth of the ratchet-wheel and with the other finger 14 out of contact therewith.

The electro-magnets are included in electric circuits, a diagram of which is shown 85 in Fig. 5, in which 17', 17' are switches controlling the electric circuits through the electro-magnets.

The transmitting device controlling the switches 17', 17' is disclosed in another application for patent filed November 2, 1918, 90 Serial No. 260,870, and forms no part of the present invention.

The operation is as follows:—

Assuming that the mechanism of the transmitter causes the switch 17' to close against the contact of conductor A, the electric current flows from the battery through magnet 16, causing its armature 15 to be attracted, moving rocker 11 and disengaging the finger 100 13 from the tooth of the ratchet-wheel 5 and permitting the ratchet-wheel to turn under the influence of the weight 8, in an anti-clockwise direction, for the angular distance of half of a tooth pitch, the finger 14 105 having thereupon moved in contact with the ratchet-wheel, thereby arresting the movement thereof. When the switch is opened,

the contacts between 17' and 18 are broken. The spring 17 pulls the rocker 11 and armature 15 carried thereby back to their original position, thereby removing the finger 14 from contact with the ratchet-wheel, permitting the ratchet-wheel to turn one-half of a tooth pitch and bringing the finger 13 into engagement with the ratchet-wheel to arrest the movement thereof. Thus, for every make and break of the electric circuit, the ratchet-wheel is released for an instant, and the force of the weight 8 operating through the cable 7 on the ratchet-wheel turns the latter one tooth pitch in an anti-clockwise direction, whereupon it is locked, awaiting the next electrical impulse.

To move the other ratchet-wheel in the reverse direction, *i. e.*, in a clockwise direction, the transmitter throws the other switch 20 against contact 18'.

By the construction described, it will be seen that the ratchet-wheels are reversely movable, *i. e.*, one thereof moves in a clockwise direction and the other moves in an anti-clockwise direction, and that the ratchet-wheels are independently movable, and do not rotate in unison, or simultaneously.

The movement of arm 2 is $\frac{1}{2}$ the algebraic sum of the movements of the wheels 4, 4. Otherwise expressed, gears 3, 4, 4 resolve the two opposite angular motions of the two ratchet-wheels 5, 5 into a single angular motion of arm 2, which is an accurate counterpart of the remote mechanism or body.

While we have described the weights 8 and the cables 7 as the means for moving the ratchet-wheels when released by the escapement mechanism, it will be understood that any other means to supply torque to the ratchet-wheels, in opposite directions, may be used.

Referring, now in detail to Figs. 3 and 4, showing a somewhat modified construction, it will be seen that this type of mechanism differs from the form shown in Figs. 1 and 2, principally in the fact that, in the form shown in Figs. 1 and 2, the magnets supply energy to operate an escapement device only, releasing the ratchet-wheels, which are supplied with an independent source of power to cause them to move; while, in the form disclosed in Figs. 3 and 4, the magnets themselves supply the source of power not only to release the wheels, but to also cause them to move.

Substantially the same type of differential gear system is used in both cases. In Figs. 3 and 4, 19, 19 designate spur or cog wheels loosely supported on the shaft 19' rotatably supported in suitable bearings in the upper ends of standards 20, 20 on a base or bed 21. The cog wheels mesh with pinions 22 rigidly supported on a pin 23 rotatably carried at the upper end of an arm 24 secured, at its

other end, to the shaft 19' so as to rotate therewith. The cog wheels 19, 19 are integral with ratchet-wheels 25, 25 provided with hubs 26, 26 encircling the shaft 19'. The teeth of the ratchet-wheels are reversely cut, 70 similarly to the ratchet-wheels of the device of Figs. 1 and 2.

Cooperating with each ratchet-wheel 25 are pawls 27, 28, of differing lengths, pivoted, at their lower ends, to opposite ends of a rocker 29 fulcrumed intermediate its ends, on a bracket 30 secured to the base or bed 21. The pawls are maintained in engagement with the ratchet-wheels by springs 38 secured to the standards 20, 20. Secured to the rocker, between the ends thereof, are fingers 31, 32 which move with the rocker and are arranged so that they alternately move between two adjacent pins 33 carried by the ratchet-wheel 25 and disposed in a circular series on the outside face of the wheel near the edge thereof. The number of pins equal the number of teeth in the wheel and are equally spaced. When the pawls 27, 28, are in normal position, the operative or 80 upper end of the finger 31 projects into the path of movement of the pins 33 and prevents the wheel 25 from turning more than one-half a tooth pitch. Likewise, if the rocker 29 is moved from normal position, the 85 finger 32 is rocked into the path of pins 33.

Secured, at one end thereof, to one end of the rocker 29 is an arm 34 carrying, at its other end, an armature 35 normally disposed out of contact with an electro-magnet 36 included in an electric circuit, such as has been described in connection with the device of Figs. 1 and 2. The armature is normally maintained out of contact with the magnet by a coil spring 37, as shown.

Each of the ratchet-wheels is peripherally engaged by a roller 39 rotatably supported at one end of a leaf-spring 40, secured, at its other end, to the bed 21. The rollers and springs act as brakes or drags on 100 the ratchet-wheels.

In operation, when the magnet 36 is energized by a flow of electric current through its windings, the armature 35 is attracted moving the rocker 29 on its pivot and causing the pawl 27 to move downward carrying the wheel 25 with it for an angular distance for one-half a tooth pitch. Simultaneously, the pawl 28 moves upward, and, at its limit of upward movement, it engages with the 110 tooth which has moved one-half way to meet it. As soon as the electric current has ceased to flow through the magnet 36, the armature 35 is elevated to its original position by the spring 37. This action causes the rocker to assume its original position, lifting the pawl 27, which, at its extreme high position, engages with the next advancing tooth of the ratchet-wheel 25. Simultaneously, the pawl 28 has been caused to move downward, carrying 120

the wheel 25 for the angular distance of one-half a tooth pitch. It is thus evident that, for every electrical impulse sent through the circuit of which the electro-magnet 36 is a part, the ratchet-wheel 25 is caused to move for an angular distance of one complete tooth pitch. The advantage of using two pawls instead of a single pawl to move the wheel 25 is that the amplitude of movement of the 10 armature 35 need be just one-half of what it would be if only one pawl were used. This construction is very desirable, because it tends to increase the speed at which the mechanism will operate. It also makes it 15 possible to operate the mechanism with less magnet strength, due to the fact that attraction for the armature varies as the square of the distance, and, since the amplitude of its movement is only one-half as 20 great, its initial distance from the magnet need be only one-half as great.

The function of the fingers 31 and 32 is to lock the wheel 25 when the pawls 27 and 28 are at rest and prevent the wheel from 25 over-running when the pawls are in either of their extreme positions.

Having described our invention, what we claim as new and desire to secure by Letters Patent, is:—

30 1. In a device for duplicating and indicating the motion of a remote rotating body, the combination with a pair of reversely and independently rotatable ratchet-wheels, of a rotatable shaft upon which said ratchet-wheels are loosely mounted, a pair of reversely and independently rotatable gear-wheels also loosely mounted on said shaft and each movable with its complemental ratchet-wheel, means controlled by the rotation of said gear-wheels for rotating said shaft, and electrically-controlled mechanism for rotating said ratchet-wheels.

2. In a device for duplicating and indicating the motion of a remote rotating body, 45 the combination with a pair of reversely and independently rotatable ratchet-wheels, of a rotatable shaft upon which said ratchet-wheels are loosely mounted, a pair of reversely and independently rotatable gear-wheels also loosely mounted on said shaft and each movable with its complemental ratchet-wheel, a member fast on said shaft and carrying revolute means meshing with said gear-wheels, and electrically-controlled mechanism for rotating said ratchet-wheels.

3. In a device for duplicating and indicating the motion of a remote rotating body, 50 the combination with a pair of reversely and independently rotatable ratchet-wheels, of a rotatable shaft upon which said ratchet-wheels are loosely mounted, a pair of reversely and independently rotatable gear-wheels also loosely mounted on said shaft 55 and each movable with its complemental

ratchet-wheel, an arm fast, at one end thereof, on said shaft and carrying, at its other end, revolute means meshing with said gear-wheels, and electrically-controlled mechanism for rotating said ratchet-wheels. 70

4. In a device for duplicating and indicating the motion of a remote rotating body, the combination with a pair of reversely and independently rotatable ratchet-wheels, of a rotatable shaft upon which said ratchet-wheels are loosely mounted, a pair of reversely and independently rotatable gear-wheels also loosely mounted on said shaft and each movable with its complemental ratchet-wheel, an arm fast, at one end thereof, on said shaft and carrying, at its other end, a pinion meshing with said gear-wheels, and electrically-controlled mechanism for rotating said ratchet-wheels. 75

5. In a device for duplicating and indicating the motion of a remote rotating body, the combination with a pair of reversely and independently rotatable ratchet-wheels, of a rotatable shaft upon which said ratchet-wheels are loosely mounted, a pair of reversely and independently rotatable gear-wheels also loosely mounted on said shaft and each movable with its complemental ratchet-wheel, a pointer carried by and revolving with said shaft, a dial-plate with 85 which said pointer operates, means controlled by the rotation of said gear-wheels for rotating said shaft, and electrically-controlled mechanism for rotating said ratchet-wheels. 90

6. In a device for duplicating and indicating the motion of a remote rotating body, the combination with a pair of reversely and independently rotatable ratchet-wheels, of a rotatable shaft upon which said ratchet-wheels are loosely mounted, a pair of reversely and independently rotatable gear-wheels also loosely mounted on said shaft and each movable with its complemental ratchet-wheel, means controlled by the rotation of said gear-wheels for rotating said shaft, electrically-controlled escapement mechanism for each of said ratchet-wheels, and means for rotating either of said ratchet-wheels, upon movement of its escapement 100 mechanism. 105

7. In a device for duplicating and indicating the motion of a remote rotating body, the combination with a pair of reversely and independently rotatable ratchet-wheels, of a 110 rotatable shaft upon which said ratchet-wheels are loosely mounted, a pair of reversely and independently rotatable gear-wheels also loosely mounted on said shaft and each movable with its complemental ratchet-wheel, and means controlled by the gear-wheels for indicating the movements of a remote rotating body and the algebraic sum of such movements. 125

8. In a device for duplicating and indicat- 130

4
ing the motion of a remote rotating body, the combination with a pair of reversely and independently rotatable ratchet wheels, of a rotatable shaft upon which said ratchet 5 wheels are loosely mounted, a pair of reversely and independently rotatable gear wheels also loosely mounted on said shaft

and integral with said ratchet wheels, means controlled by the rotation of said gear wheels for rotating said shaft and electrically controlled mechanism for rotating said ratchet wheels. 10
